MASK STRUCTURE

James Edward Duggan, New Brighton, Pa.

Application January 6, 1943, Serial No. 471,500

13 Claims. (Cl. 91—65)

This invention relates generally to devices that are used to protect one or more surfaces or portions of an article from paint or plating material applied to adjacent or other predetermined surfaces or portions thereof, and refers more particularly to a mask structure applicable to a stub shaft or cylindrical projection of a gear or other element.

Heretofore, it has been customary to apply paint or plating material to certain surfaces of the gear from which the stub shaft projects and when this is done some of the paint or plating material oftentimes splatters or falls onto the bearing surfaces of the stub shaft and then has to be removed. To protect the stub shaft from such paint or plating material various devices, usually in the form of adhesively applied masks or taped sheets or strips, have been employed on the shafts. Such devices sometimes failed to cover or protect the surface of the shaft at the juncture thereof with the gear and usually disfigured or marred the engaged surfaces of the shaft when such devices were applied or removed. Moreover, such devices were unusable after once being applied and had to be scrapped.

Thus, one of the essential objects of the present invention is to provide a durable mask structure that may be easily and quickly applied and removed without marring the engaged surfaces and that will stand repeated handling and use.

Another object is to provide a mask structure that is simple in construction, economical to manufacture and efficient in operation.

Another object is to provide a mask structure that is so constructed that it forms a tight seal with the engaged surface to preclude paint or plating material from seeping or passing under the mask onto the shaft.

Another object is to provide a mask structure that includes a vacuum-cup portion to effectively hold the mask structure in proper masking position when applied to the shaft.

Another object is to provide a mask structure that may be manipulated in such a way that it not only may be moved longitudinally of the shaft but will form automatically a tight seal with the adjacent portion of the gear when it reaches the proper masking position.

Other objects, advantages and novel details of construction of this invention will be made more apparent as this description proceeds, especially when considered in connection with the accompanying drawing, wherein:

Figure 1 is a top plan view of a gear provided upon opposite sides thereof with axially aligned

stub shafts, and showing in section a mask embodying my invention applied to one of the shafts;

Figure 2 is an elevational view of the mask per se;

Figure 3 is an end view of the mask; and

Figure 4 is another end view of the mask;

Figure 5 is a view similar to Figure 1 but showing a slight modification.

Referring now to the drawing, A is a gear having integral stub shafts B and C projecting laterally from opposite sides thereof, and D is a mask embodying my invention for protecting either shaft B or C from paint or plating material applied to the adjacent side of the gear A.

In the present instance, the mask D is made of rubber or rubber composition and constitutes a protecting sleeve for either shaft B or C.

As shown, the mask D comprises a hollow globular body 10 provided at diametrically opposite sides with circular holes 11 and 12 and provided at one of said sides in substantially concentric relation with the hole 12 with a laterally projecting concavo-convex annular flange 13. The walls

20 of the body 10 and of the flange 13 are relatively thick, hence the edges 14 and 15, respectively, of the openings 11 and 12 are relatively wide and provide annular surfaces for surface to surface engagement with the shaft B at longitudinally spaced points thereof. Preferably the diameter

25 of the body 10 plus the length of the flange 13 is substantially equal to the length of the shaft B to which it is applied. Hence, the entire surface of the shaft is covered and protected when the mask is in proper masking position. In fact, the shaft B is not only covered but there is a tight seal provided between the edge 16 of the flange 13 and the adjacent side or surface of the gear A. In this connection it will be noted that the

30 thickness of the flange 13 is such that a surface to surface engagement of considerable width is provided between the edge 16 of said flange and the adjacent surface of the gear A.

35 In use, the flanged end of the mask D is initially slipped onto the free end of the shaft B. The globular body 10 is then squeezed or compressed by hand and urged toward the gear A. This will cause the edge 15 of the opening 12 to open wider to receive the shaft B. The body

40 10 is then released and again squeezed to advance the mask on the shaft B toward the gear A. When the body 10 is repeatedly squeezed and released as aforesaid the mask D will not only "walk" upon the shaft to masking position but 45 will cause the flange 13 to abut and bear firmly

against the adjacent side of the gear A to form a tight seal therewith. In fact, the squeezing of the body expels air from the space 20 therein through one or both openings 11 or 12 so as to create a vacuum between the body 10 and shaft B which, in cooperation with the surface to surface engagement between the shaft B and the relatively thick edges 14 and 15 of the body, will effectively maintain the mask in proper masking position on the shaft. Moreover, the diameter of the holes 11 and 12 relative to the shaft B and the resiliency of the rubber from which the mask is formed is such that pressure tight joints are provided between the shaft B and said edges 14 and 15 of the body when the mask is in proper masking position. Such joints will prevent any slippage of the mask relative to the shaft and thus will maintain the seal aforesaid between the flange and the gear. As a result, there is no possibility of paint or plating material applied to the gear A reaching the shaft B. The same is also true of the other shaft C when it is covered by a similar mask.

In Figure 5 I have illustrated a slight modification wherein the mask D' is elongated in form for engagement with a longer shaft B'. As shown the body 10' of the mask has thick edges 30 and 31, respectively, corresponding to the thick edges 14 and 15 illustrated in Figure 1, to provide the proper tight surface to surface engagement with the shaft, but has relatively thin intermediate connecting walls 32 which may be squeezed as aforesaid when it is desired to advance the mask on the shaft to masking position. Thus, the over-all amount of rubber or its equivalent used in the manufacture of this elongated mask D' is approximately the same as that used in the shorter mask D.

Thus, from the foregoing it will be apparent that I have provided a mask structure that may be easily and quickly applied to or removed from a shaft or similar element without marring the engaged surfaces or the paint or plating material applied to the gear A and that will effectively protect such shaft from the paint or plating material while it is being applied to the gear or similar element on said shaft.

What I claim as my invention is:

1. A mask structure comprising a globular body provided at substantially diametrically opposite sides thereof with holes and provided at one of said sides in substantially concentric relation to the hole therein with a laterally projecting substantially concavo-convex annular flange.

2. A mask structure formed of resilient material and comprising a globular body provided at substantially diametrically opposite sides thereof with holes and provided at one of said sides in substantially concentric relation to the hole therein with a laterally projecting outwardly opening cup shaped flange.

3. A one piece mask structure formed entirely of rubber or rubber composition and comprising a hollow globular body provided in opposed walls thereof with holes and provided upon the outside of one of said walls in substantially concentric relation to the hole therein with a laterally projecting substantially concavo-convex annular flange.

4. A mask structure comprising a hollow globular resilient body provided in opposed walls thereof with holes and provided upon the outside of one of said walls in substantially concentric relation to the hole therein with a laterally projecting outwardly opening cup shaped flange.

5. A mask structure formed of resilient material and comprising a hollow closed body provided in opposed walls thereof with aligned holes and provided upon the outside of one of said walls around the edges of one of said holes with a laterally projecting substantially concavo-convex annular flange.

6. A mask structure of the class described formed entirely of rubber or rubber composition and comprising a hollow globular body provided with aligned holes for receiving a shaft and provided upon the outside of the globular body in substantially concentric relation to one of said holes with a laterally projecting substantially concavo-convex annular flange for sealing engagement with one side of a gear on said shaft.

7. A mask structure of the class described formed entirely of rubber or rubber composition and comprising a hollow globular body provided in opposed walls thereof with holes for receiving a shaft and provided upon the outside of the body in substantially concentric relation to one of said holes with a laterally projecting substantially concavo-convex annular flange for sealing engagement with one side of a gear on said shaft, the walls of said body and of the flange being of such thickness that the edges of said holes and of said flange provide relatively wide surface to surface engagement respectively with said shaft and said gear.

8. Means for protecting a shaft from paint or plating material applied to an article on said shaft, comprising a globular body of resilient material provided at diametrically opposite sides thereof with holes for receiving said shaft and provided at one of said sides in substantially concentric relation with the hole therein with a laterally projecting concavo convex annular flange for sealing engagement with the article on said shaft.

9. Means for protecting a shaft from paint or plating material applied to an article on said shaft, comprising a hollow body of resilient material provided in opposite walls thereof with aligned holes for receiving said shaft and provided at one of said walls around the edges of the hole therein with a laterally projecting outwardly opening cup shaped flange for sealing engagement with the article on said shaft, the hollow body itself forming a chamber, and the aligned holes being of such size relative to the shaft that the chamber is closed when the holes receive said shaft.

10. Means for protecting a shaft from paint or plating material applied to an article on said shaft, comprising a hollow body of resilient material provided in opposite walls thereof with aligned holes for receiving said shaft and provided at one of said walls around the edges of the hole therein with a laterally projecting outwardly opening cup shaped flange for sealing engagement with the article on said shaft, the walls of said body at said holes being relatively thick whereby the edges of said holes provide relatively wide surface to surface sealing engagement with said shaft, the hollow body itself forming a chamber, and the aligned holes being of such size relative to the shaft that the chamber is closed when the holes receive said shaft.

11. Means for protecting a shaft from paint or plating material applied to an article on said shaft, comprising a hollow body of resilient material provided in opposite walls thereof with aligned holes for receiving said shaft and provided at one of said walls around the edges of

the hole therein with a laterally projecting outwardly opening cup shaped flange for engagement with the article on said shaft, the flange being relatively thick whereby the free end thereof provides relatively wide surface to surface sealing engagement with said article, the hollow body itself forming a chamber, and the aligned holes being of such size relative to the shaft that the chamber is closed when the holes receive said shaft.

12. A mask structure of the class described comprising a compressible hollow body provided in opposed walls thereof with aligned holes for receiving a shaft and provided upon the outside of one of said walls in substantially concentric relation to one of said holes with a laterally projecting outwardly opening cup shaped flange for sealing engagement with one side of an element on said shaft, the hollow body itself forming a chamber, and the aligned holes being of such size 20

relative to the shaft that the chamber is closed when the holes receive said shaft.

13. A mask structure of the class described comprising a compressible hollow body having in opposed walls thereof aligned holes for receiving a shaft and provided on the outside of one of said walls around the edges of one of said holes with a laterally projecting outwardly opening cup shaped flange for sealing engagement 5 with an abutment on said shaft, the body itself forming a chamber, said body being formed of resilient material and adapted to be advanced on said shaft toward said abutment while alternately compressing and releasing the body, the 10 size of the holes relative to the shaft being such that a vacuum is created in said chamber when the body is released following compression 15 thereof.
